UNITED STATES PATENT OFFICE.

JOHN A. BOWYER, OF SYCAMORE, ILLINOIS, ASSIGNOR TO THE TURNER BRASS WORKS, OF SYCAMORE, ILLINOIS, A CORPORATION OF ILLINOIS.

APPLIANCE FOR HAND-TORCHES.

1,107,023.

Specification of Letters Patent. Patented Aug. 11, 1914.

Application filed October 20, 1913. Serial No. 796,281.

To all whom it may concern:

Be it known that I, JOHN A. BOWYER, a citizen of the United States, and a resident of Sycamore, in the county of Dekalb and 5 State of Illinois, have invented certain new and useful Improvements in Appliances for Hand-Torches; and I do hereby declare that the following description of my said invention, taken in connection with the accompanying sheet of drawings, forms a full, 10 clear, and exact specification, which will enable others skilled in the art to which it appertains to make and use the same.

This invention has general reference to an 15 appliance for hand torches.

It consists, essentially, in the novel and peculiar combination of parts and details of construction, as hereinafter first fully set forth and described and then pointed out 20 in the claims.

In the drawing already referred to which illustrates my said invention more fully, Figure 1, is a longitudinal, vertical section of a typical hand torch showing my appliance in elevation, the dotted lines being employed to indicate the said invention in a different position upon the torch. Fig. 2 is a transverse, vertical section in the direction of the arrow 25 pointers, in line 2—2 of Fig. 1. Fig. 3 is a partially exposed horizontal section in the direction of the arrow pointers in line 3—3 of Fig. 1, the remainder of the parts of said figure being in elevation. Fig. 4 is a trans- 30 verse section of the flame or burner tube in line 4—4 of Fig. 3. Fig. 5 is a segment of a fragment in line 5—5, of Fig. 5. Fig. 6 is a plan of a fragment of a sheet metallic blank employed in my invention.

Like parts are indicated by corresponding 40 symbols or characters of reference in the drawing.

The object of this invention is the production of means whereby soldering irons and 45 the like may be heated in any of the typical hand torches now upon the market, said means being so constructed that no change of the torch is required aside from slipping my appliance over the burner thereof and 50 fastening the same by a thumb or similar screw. This device is a valuable adjunct for all artisans using a hand torch, because every worker employing such a torch as an article of his kit must frequently use a soldering iron. Such irons are now heated by

holding the irons in front of the flame of the torch, a time and fuel-wasting proposition. With my appliance a workman may insert a soldering iron therein and then go about his business until the same is hot enough for use. Or the worker may employ two irons, using one while the other is being heated. And when it is understood that my device may be applied to or removed from any hand torch, by a mere twist of the hand without any change to the torch itself, its 60 practicability becomes self evident.

In the drawings, A represents the body of the usual hand torch. In the present instance the top B is shown as drawn integrally with the body A, while a bottom C, is crimped in position by a base flange D; the whole when properly soldered, forms the tank F. In the top near one side thereof is formed an opening surrounded by a sleeve 1 having an external flange 2, said sleeve is both exteriorly and internally screw-threaded, the former to receive a jam nut 3, adapted to form a tight joint between the flanged portion 2 and the metal of the top B, and the latter to accept a finger actuated filling plug 4. Located vertically alongside the body A of the tank F, there is provided a hand air pump G, which at the same time serves as a handle for the tank and also provides means to create a pressure within said tank in a manner easily understood. Conveniently in top B near the edge thereof and at a point usually directly opposite the combined pump and grasping handle G, there 75 is formed an opening to receive an annular, flanged sleeve 5, the lower end of which is exteriorly threaded. Fitted over the sleeve there is a jam nut 6 to form a tight joint between said flanged sleeve 5 and the opening 80 in the top B provided therefor. The interior of sleeve 5 is internally threaded for the reception therein of a length of piping 7, the lower end of which extends into tank F to near the bottom thereof, while the upper extremity is fitted into a typical angular needle valve 8, the free end of which generally points slightly upwardly, as shown, and possesses at its open end an upwardly projecting tube 9. This tube has a series 85 of peripheral perforations 10, is open ended and is termed the burner tube or flame tube. After the tank F has been filled with the required hydrocarbon fuel and a sufficient atmospheric pressure created therein by ma- 90

nipulation of pump G, the handle 11, actuating the stem 11^a, in needle valve 8, is slightly opened for ingress of fuel into the burner tube 9, which fuel is then ignited to heat the 5 said tube sufficiently to insure vaporization, after which an intense flame will issue from the open end of the burner, the necessary amount of oxygen being supplied through the perforations 10. The article just 10 described is the ordinary hand torch in readiness to perform its usual functions.

My newly invented appliance comprises an integral sheet metallic plate 12, the blank of which is cut to such shape as to form a 15 flat rectangular bottom 13, having parallel, bent up sides 13^a and 13^b, whose upper edges at one end are of arcuate contour merging with the bottom 13 at the dotted bending line a. Blank 12 has lips 14 and 15 along 20 both sides, which lips are bent up along the dotted lines b and c at an interior width equaling the external distance between the sides 13^b and 13^a. The said blank 12 is now bent up from the line a to form a cover for 25 the sides 13^b and 13^a, with the lips 14 and 15 closely embracing the same. The end of this cover 16 is coincident with the perpendicular edges 17 and 18 of the side walls 13^a and 13^b, and, rivets 19 are passed through 30 said side walls and lips 14 and 15 to firmly hold together the integral structure now designated S.

The bottom 13 and top 16 are provided with openings 20 for exit of hot gases, and 35 in said bottom, near the open end of the structure 5 is punched an oblong opening 21, which is provided for passage therethrough of a bracket 22, which is internally bored so as to be a free fit over burner or 40 flame torch 9 hereinbefore described. This bracket has two lugs 23 and 24 and rivets 23^a and 24^a; it is riveted to bottom 13 of structure S. The internal bore of bracket 22 is spaced at such a height that when 45 burner tube 9 is passed therethrough, the bottom of said tube will rest upon the bottom 13 of the heater or structure S. The bottom of the bracket 22 is tapped and fitted for a thumb screw 25, by the manipulation 50 of which the heater S may be secured to the

burner tube 9 in any desired position, be it vertical or horizontal, or at any angle between.

While herein I have disclosed the most preferred form of construction, I reserve the 55 right to make such changes and alterations therein which would suggest themselves to the skilled mechanic or permitted under the doctrine of mechanical equivalents.

Having thus fully described my invention, 60 I claim as new and desire to secure to myself by Letters Patent of the United States:—

1. An appliance for a hand torch having 65 a fuel tank and a burner tube extending outwardly and upwardly therefrom; a heating receptacle comprising a floor, roof and sides, the burner of said torch extending within 70 said receptacle and adjustably fixed to the said floor thereof whereby the angularity of 75 said receptacle may be varied.

2. An appliance for a hand torch having 80 a fuel tank and a burner tube extending outwardly and upwardly therefrom; a heating receptacle comprising a floor, roof, and 75 sides, an internally bored bracket fixed to said floor, fastening means on said bracket exteriorly of said receptacle, said burner tube being adapted to enter the bore of said bracket and to be maintained in position 85 within said receptacle by said fastening means.

3. An appliance for a hand torch having 85 a fuel tank and a burner tube extending outwardly and upwardly therefrom; a heating receptacle comprising a floor, roof, and sides, said roof sloping forwardly to said 90 bottom, the burner of said torch extending into said receptacle along the floor thereof and fixed in position adjustably, whereby the angularity of said receptacle with respect to said fuel tank may be varied.

In testimony whereof I have hereunto set my hand in the presence of two subscribing witnesses:

JOHN A. BOWYER.
